UNITED STATES PATENT OFFICE.

WALTER V. KRAFT, OF CLINTON, ILLINOIS.

WATER HEATER.

Application filed February 17, 1927. Serial No. 169,003.

The invention relates to improvements in devices for heating water and while the primary intent of such device is for use in connection with a heating radiator and water circulating pipes, it is obvious that said heater might be employed for other purposes.

It is the object of the invention to provide a new and improved construction for a water heater in which novel provision is made for outwardly deflecting products of combustion to points at which they will perform additional work, before they are permitted to escape.

With the foregoing in view, the invention resides in the novel subject matter herein-after described and claimed, the description being supplemented by the accompanying drawing.

Fig. 1 is a vertical sectional view through a water heater as indicated by line 1—1 of Fig. 2.

Fig. 2 is a vertical sectional view at right angles to Fig. 1, as denoted by the line 2—2 of Fig. 1.

In the drawing above briefly described, the numeral 3 designates a suitable chamber adapted to contain a gas burner 4 or other desired flame producing means. Around this chamber, is a shell 5, a water space 6 being provided between said chamber and shell. This space 6 may be provided with any desired inlet and outlet means 7—8, for the water to be heated.

Water circulating tubes 9 which are preferably of the shape shown in Fig. 1, are disposed within and secured to the chamber 3, the lower portions of said tubes being disposed over the burner 4, while the upper portions of said tubes are disposed vertically and arranged in two parallel rows. The tubes 9 communicate at their opposite ends with relatively low and high portions of the water heating space 6 and they assist materially in permitting rapid heating of the water.

An outlet pipe 10 is provided for the products of combustion, said pipe extending horizontally across the upper portion of the chamber 3, between the above-named parallel rows of vertical tube portions. The lower side of the pipe 10 is imperforate and serves as a baffle to outwardly deflect the rising products of combustion against the upper ends of the tubes 9 and toward the side wall of the chamber 3, insuring that maximum heating effi-

ciency be attained from these products of combustion before they escape. The upper portion of the pipe 10 is formed with means, however, for admitting the products of combustion to said pipe, after they have lost most of their heating efficiency. This means is preferably in the form of a longitudinal slot 11, which may be formed by cutting away substantially the upper half of the pipe 10. This pipe is shown provided with a closed end 12 within the chamber 3 and with an upturned end 13 at the exterior of said chamber, connected with an appropriate vent pipe 14.

Preferably, a metal jacket 15 is provided around the shell 5, and the space between said jacket and shell may be packed with asbestos 16 or other desired insulating material.

By providing the novel construction shown and described, or a substantial equivalent thereof, a rather simple and inexpensive, yet an efficient and very desirable water heater is produced. Hence, the details disclosed are preferably followed. However, within the scope of the invention as claimed, variations may be made.

I claim:

In a water heater, a chamber to contain flame-producing means, a water-containing shell spaced around said chamber, water tubes in said chamber communicating with the interior of said shell, said tubes having vertical upper portions disposed in two spaced parallel rows within the chamber, the lower portions of one row of tubes being curved outwardly in one direction toward one side of said chamber and the lower portions of the other row being curved outwardly in the opposite direction from and between the curved lower portions of the first mentioned row, and an outlet pipe for the products of combustion extending horizontally across the upper end of said chamber and disposed between said rows of vertical tube portions; said pipe having an imperforate lower portion to deflect the products of combustion outwardly against said vertical tube portions, the upper portion of said pipe having means for admitting the products of combustion.

In testimony whereof I have hereunto affixed my signature.

WALTER V. KRAFT.
